SEPARATION OF AIR

Kenneth Cecil Smith, Carshalton, Surrey, England, assignor to The British Oxygen Company Limited, London 6, England, a British company

Filed May 16, 1963, Ser. No. 280,868

Claims priority, application Great Britain, May 29, 1962, 20,693/62

2 Claims. (Cl. 62—13)

This application relates to a process for the separation from air of a gaseous product containing about 60 to 70% by volume of oxygen.

Oxygen-enriched air containing about 60 to 70% by volume of oxygen is a valuable commodity for many purposes, for example in the manufacture of steel, and its production by the low-temperature separation of air involves a power consumption which is substantially lower than is required for the production of an equivalent output of high-purity oxygen in a conventional air separation plant.

It is an object of the present invention to provide a method for producing enriched air containing about 60 to 70% by volume of oxygen by the low-temperature separation of air in which the power consumption is minimised.

According to the present invention, a process for the production from air of a gaseous product containing about 60 to 70% by volume of oxygen comprises subjecting compressed air, previously cooled to condensation temperature and freed from condensable impurities, to a two-stage rectification to produce a first liquid fraction enriched in oxygen to an extent considerably less than that required in the final gaseous product, partially vaporising said first liquid fraction by heat exchange with gaseous nitrogen from the first stage of the two-stage rectification to produce a second liquid fraction having an oxygen content equal to that required in the gaseous product, and an oxygen-rich gaseous fraction, the gaseous nitrogen itself being condensed, using the condensed nitrogen so formed to provide reflux liquid in both stages of the two-stage rectification, recycling the oxygen-enriched gaseous fraction to the second stage of the two-stage rectification and vaporising the second liquid fraction to provide the required gaseous product, by heat exchange with incoming air.

The second liquid fraction may be vaporised by heat exchange with the incoming air before the latter is subjected to rectification, or, alternatively, it may be vaporised in a partial condenser forming the first rectification stage, by heat exchange with air undergoing rectification therein.

The compressed air is conveniently cooled to saturation temperature and freed from condensable impurities by heat exchange with outgoing gaseous products in switch exchangers, which term as used herein includes both regenerators and reversing exchangers. The switch exchangers may be "balanced" by any suitable method. A particularly convenient method is to withdraw a side-stream of air from the switch exchangers and to feed it after suitable adjustment of its temperature and pressure, and, if necessary, removal of any residual condensable impurities, to one stage of the two stage rectification. For example, the side-stream of air may be cooled by expansion in an expansion turbine, after removal of the condensable impurities, and the expanded air stream fed directly to the second stage of the two-stage rectification. Alternatively, the side-stream of air can be used to preheat a minor portion of the gaseous nitrogen leaving the first rectification, this minor portion after preheating being expanded in a turbine to the second-stage pressure and combined with gaseous nitrogen leaving the second stage of the

2

rectification before this nitrogen passes to the switch exchangers.

Three embodiments of the invention designed to produce enriched air containing 70% by volume of oxygen will now be described in more detail with reference to the drawings accompanying the Provisional Specification in which FIGURE 1 is a flow-sheet of the first embodiment;

FIGURE 2 is a flow-sheet of the second embodiment. FIGURE 3 is a flow-sheet of the third embodiment.

Referring to FIGURE 1, air compressed to 2.85 atma. and which has been cooled and freed from water vapour and carbon dioxide is further cooled to its condensation temperature in a vaporiser 1 by heat exchange with an evaporating liquid fraction produced as hereinafter described. The air is then fed to the lower column 2 of a two-stage rectification system where it is separated into a gaseous nitrogen fraction and a liquid fraction somewhat enriched in oxygen. The liquid fraction is fed through an expansion valve 3 to the upper column 4 of the two-stage rectification system, where it is separated into a gaseous nitrogen fraction which leaves the top of the column at 5 and a liquid fraction containing 48% of oxygen which collects at the bottom of the column and is thence fed to a condenser-evaporator 6 where it is partially vaporised to produce a liquid fraction containing 70% of oxygen and a gaseous fraction containing 37% of oxygen by heat exchange with condensing gaseous nitrogen from the lower column 2. The liquid and gaseous fractions are separated in a separator 7 and the gaseous fraction is recycled to the upper column 4 at an appropriate point. The liquid fraction is expanded to atmospheric pressure through an expansion valve 8 and vaporised in exchanger 1 against incoming air to provide the required gaseous product containing 70% oxygen.

A part of the nitrogen condensed in the condenser-evaporator 6 is returned to the top of the lower column 2 to serve as reflux therein, and the remainder is expanded through a valve 9 into the top of the upper column 4 to provide reflux liquid for this column.

A rather more elaborate scheme for the production of enriched air containing 70% oxygen is shown in FIGURE 2.

In this form of the invention, air is compressed to 3.2 atma. in a compressor 10, precooled in a precooler 11, and further cooled by returning separation products in two pairs of regenerators 12 and 13 with the simultaneous removal of condensable impurities. At a pressure of about 3 atma, the main portion of the air then enters a partial condenser 14, forming the first stage of a two-stage rectification system; it passes in heat exchange with evaporating liquid product as hereinafter described and in which it is separated into a gaseous nitrogen fraction and a liquid fraction containing 40% oxygen.

The liquid fraction is passed through an exchanger 15 in heat exchange with gaseous nitrogen leaving the second stage of the rectification system as hereinafter described and is then expanded through a valve 16 into an adiabatic column 17 forming the second stage of the rectification system, and in which it is separated into a gaseous nitrogen fraction leaving the top of the column 17 and a liquid fraction containing about 51% oxygen which collects at the bottom of the column.

A minor part of the gaseous nitrogen fraction leaving the top of the partial condenser 14 is preheated in a turbine preheater 18 by heat exchange with air withdrawn as a sidestream from the regenerators 12 and 13 and is then expanded with the performance of external work in a turbine 19 to a pressure of 1.2 atma. The exhaust from the turbine joins the waste nitrogen leaving the top of the column 17.

The remainder of the gaseous nitrogen fraction leaving the partial condenser 14 is condensed in a condenser-evaporator 20 by heat exchange with the liquid fraction containing about 51% oxygen from the bottom of the adiabatic column 17. A part of the condensed nitrogen is returned to the partial condenser 14 to act as reflux liquid therein, whilst the remainder after passing in heat exchange with gaseous nitrogen leaving the column 17 in an exchanger 21 is fed through an expansion valve 22 into the top of the adiabatic column 17 to provide reflux liquid for this column.

The partially-vaporised oxygen-rich fraction leaving the condenser-evaporator 20 is separated in an equaliser 23 into a vapour fraction containing 37% oxygen which is returned to the adiabatic column 17 through a line 24, and a liquid fraction in equilibrium with this and containing 70% oxygen.

This liquid fraction is slightly expanded through a valve 25 into the partial condenser 14 where it is completely vaporised to provide the gaseous product containing 70% oxygen, and from which it is withdrawn for use, after giving up its cold content to incoming air in the regenerator 12.

Yet another alternative method is shown in FIGURE 3, which differs from FIGURE 2 in that the side-stream from the regenerators passes through a carbon dioxide absorber 26, then through the turbine 19, and enters the adiabatic column 17. In this modification, 20-25% of the entering air is bled from the columns and passes via the carbon dioxide absorber 26 and turbine 19 to the adiabatic column 17, and 75-80% of the air passes to the partial condenser 14, as in the embodiment shown in FIGURE 2.

The above examples are of only three embodiments of the invention, and other embodiments are possible; for example, a three regenerator system could be used instead of the two regenerator system shown in FIGURES 2 and 3, and other methods of "balancing" the regenerators could be used, such as the so-called "Trumpler pass" method.

I claim:

1. A process for the production from air of a gaseous product containing about 60 to 70% by volume of oxygen comprising the steps of subjecting compressed air, previously cooled to its saturation temperature and freed from carbon dioxide and water to a first stage rectification to produce a first liquid fraction enriched in oxygen and a first gaseous nitrogen fraction, subjecting said first liquid fraction enriched in oxygen to a second stage rectification to produce a second liquid fraction, further enriched but to an extent considerably less than that required in the final gaseous product, and a second gaseous nitrogen fraction, withdrawing the second liquid fraction from the second stage rectification zone and passing the entire second liquid fraction in heat exchange with at least a part of said first gaseous nitrogen fraction to partially vaporize said second liquid fraction and produce a third gaseous fraction having a higher oxygen content than air and a residual liquid fraction having an oxygen content equal to that required in the gaseous product, at least a part of said first gaseous nitrogen fraction itself being condensed to provide condensed nitrogen, using said condensed nitrogen to provide reflux liquid in both the first and the second stage rectification, recycling said third gaseous fraction to said second stage rectification, and vaporizing said residual liquid fraction to provide the required gaseous product by heat exchange with incoming air, cooling at least a part of said compressed air to

saturation temperature and freeing at least a part of said compressed air from condensable impurities by heat exchange with outgoing gaseous products in switch exchangers, withdrawing compressed air as a side-stream from said switch exchangers and subsequently feeding the compressed air to a stage of said first stage rectification, preheating a minor part of the first gaseous nitrogen fraction by heat exchange with said air withdrawn as a side-stream from said switch exchangers, said minor part being expanded in an expansion turbine and combined with said second gaseous nitrogen fraction, said air withdrawn as a side-stream from said switch exchanger leaving said heat exchange step being combined with the main stream of compressed cooled air leaving said switch exchangers.

15 2. A process for the production from air of a gaseous product containing about 60-70% by volume of oxygen comprising the steps of subjecting compressed air, previously cooled to its saturation temperature and freed from carbon dioxide and water to a first stage rectification

20 20 to produce a first liquid fraction enriched in oxygen and a first gaseous nitrogen fraction, subjecting said first liquid fraction enriched in oxygen to a second stage rectification to produce a second liquid fraction, further enriched but to an extent considerably less than that required in the

25 final gaseous product, and a second gaseous nitrogen fraction, withdrawing the second liquid fraction from the second stage rectification zone and passing the entire second liquid fraction in heat exchange with at least a part of said first gaseous nitrogen fraction to partially vaporize

30 said second liquid fraction and produce a third gaseous fraction having a higher oxygen content than air and a residual liquid fraction having an oxygen content equal to that required in the gaseous product, at least a part of said first gaseous nitrogen fraction itself being condensed to provide condensed nitrogen, using said condensed nitrogen to provide reflux liquid in both the first and the second stage rectification, recycling said third gaseous fraction to said second stage rectification, and

35 vaporizing said residual liquid fraction to provide the required gaseous product by heat exchange with incoming air, cooling at least a part of said compressed air to saturation temperature and freeing at least a part of said compressed air from condensable impurities by heat exchange with outgoing gaseous products in switch exchangers, withdrawing compressed air as a side-stream from said switch exchangers after removal of residual condensable impurities therein and subsequently expanding said compressed air in an expansion turbine and feeding the expanded air to the second stage of rectification.
